I. BARNES

MUSICAL INSTRUCTION DEVICE

Filed Oct. 17, 1924

George Barnes
INVENTOR

BY
Maurice Oppenheimer
ATTORNEY

UNITED STATES PATENT OFFICE.

IRVING BARNES, OF WESTWOOD, NEW JERSEY.

MUSICAL-INSTRUCTION DEVICE.

Application filed October 17, 1924. Serial No. 744,108.

To all whom it may concern:

Be it known that IRVING BARNES, a citizen of the United States, residing at Westwood, in the county of Bergen and State of New Jersey, has invented certain new and useful Improvements in Musical-Instruction Devices, of which the following is a specification.

This invention relates to musical instruction devices and more particularly to means adapted to be mounted on an instrument such as a piano or organ for correlating the position of the notes of the musical scale with the key-board of the instrument.

An object of the invention is to provide a device of the character described to enable beginners studying music to quickly familiarize themselves with the location of each note on the staves with its corresponding key of the key-board of the piano, organ or like instrument.

Another object of the invention is to provide a device of the character described which is simple in construction, quickly and easily applied to a key-board, inexpensive to manufacture and practical to a high degree for the purposes described.

Other objects of the invention will in part be obvious and in part hereinafter set forth.

The invention accordingly consists in the features of construction, combinations of elements and arrangement of parts which will be exemplified in the construction hereinafter described and of which the scope of application will be indicated in the following claims.

In the accompanying drawing, in which is shown one of the various possible illustrative embodiments of this invention,

Fig. 1 is a plan view of a device embodying the invention laid flat;

Fig. 2 is a fragmentary front elevational view of a portion of a musical instrument and key-board showing the device applied thereto; and

Fig. 3 is a cross-sectional side view corresponding to Fig. 2.

Referring in detail to the drawing, 10 indicates generally a device embodying the invention which is seen to comprise a sheet of comparatively stiff but foldable material such as card board or the like, having printed thereon a bass and treble staff, 11 and 12 respectively, with notes 13 running in consecutive regular rotation from the bass

to the treble clef. The notes 13 preferably extend an octave above middle C, 14, on the treble staff 12 as shown in Fig. 1, and a pair of spaced lines 15 may be printed between and parallel to the two staves for the purpose hereinafter to appear. The edge portion 16 of the sheet 10 below the bass staff 11 is proportioned and ruled off in division 17 to correspond in width to the keys of a standard key-board of a piano, 60 organ, or the like instrument, and has openings 18 formed therein of proper size to fit over the usual black keys thereof. Dotted lines 18^a may be provided on the chart to extend vertically down from each of the notes 13 to their corresponding key divisions 17, each of the latter being preferably lettered adjacent the lower edge of the charts 10 as at 19 to conform with the musical scale A, B, C, etc. If desired, additional 65 sets of letters 20 and 21 indicating the notes of the musical scale may be printed under each note and below the staves 11 and 12 as shown in Figs. 1 and 2.

In order to facilitate handling the sheet 80 19, it is preferably divided into a plurality of equal separate sections 22, four as is here shown.

Referring now to Figs. 2 and 3, in which is illustrated a practical application of the invention 23 and 24 denote white and black keys on a standard key-board of a musical instrument 25, only a fragmentary portion of the latter being shown, and 26 and 27 indicate respectively the usual horizontal and 85 vertical music sheet or book rests.

Each of the sections 22 is creased and adapted to be folded on the lines 15 so that the portion 28 of the sheet 10 above the upper line 15 which has the treble staff 12 95 thereon may be bent forwardly with respect to the portion 29 between said lines 15, the portion 28 being arranged to bear against rest 27 and portions 29 to lie on rest 26, while the portion 30 below the lower line 15 may 100 be bent backwardly substantially at right angles to portion 29. The lower portion 16 is also creased and adapted to be folded on a line 31 drawn through the rear of the openings 18, said portion 16 being bent at right 105 angles to the adjoining portion 30 which has the bass staff 11 thereon, so that the openings 18 thereon are adapted to receive the black keys 24.

The sheet 10 may be then applied to the 110

instrument 25 starting at either end by arranging the sections 22 in numerical succession abutting one another, fitting the portion 16 over the key-board with the black keys extending through the openings 18 and the upper portion 28 supported on the vertical rest 27. The sheet 10 shown in Fig. 1 is for a standard full size range key-board of seven and one-third octaves. Shorter key-boards may of course be fitted by cutting away the end division 17 of the chart. With the device in position on the instrument 25, it is clear that the keys 23 and 25 are left free for playing and each key is conspicuously identified by its corresponding note on the staves, thus enabling beginners to quickly familiarize themselves with the location of the notes and correlated keys.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:—

1. A device of the character described adapted to be applied to a key-board of a musical instrument, comprising a sheet having notes arranged thereon on two spaced staves in the order of the musical scale, a section of said sheet being adapted to overlie a portion of the key-board to position the notes in correlation with the key-board, said sheet being constructed to fold on the portions thereof between the two staves and adjacent said section to conform with parts of the instrument.

2. A device of the character described adapted to be applied to a key-board of a musical instrument, comprising a sheet having notes arranged thereon on two spaced staves in the order of the musical scale, a section of said sheet being adapted to overlie a portion of the key-board to position the notes in correlation with the key-board, said sheet being constructed to fold on the portions thereof between the two staves and adjacent said section to conform with parts of the instrument, said section having openings therein adapted to receive the black keys of the key-board.

In testimony whereof I affix my signature.
IRVING BARNES.
